METHOD OF AND APPARATUS FOR SEVERING INTO LENGTHS COILED FILAMENT WIRE

Heinrich Asmussen, Berlin-Steglitz, and Joseph Riess, Berlin, Germany, assignors to General Electric Company, a corporation of New York

Application October 16, 1936, Serial No. 106,044
In Germany November 8, 1935

10 Claims. (Cl. 140—140)

Our invention relates to a method of and apparatus for severing into lengths coiled filament wire for electric incandescent lamps and similar devices. Coiled filaments are formed by coiling a continuous length of filament wire around a mandrel to form closely coiled sections which are separated at regular intervals by loosely coiled intermediate sections, the said wire being severed at the middle of the loosely coiled sections to form the individual filaments. Difficulty has been experienced in devising automatic machinery to cut the filament wire into lengths since even the slightest deviations in length of the intermediate loosely coiled portions would displace the location of the cut which was originally adjusted to the center of the intermediate portion. The errors in this method are cumulative so that after a certain time the lengths of the filament and their end sections vary too much from the original setting.

According to our invention the continuously wound filament wire is moved longitudinally through a beam of light, and the variation in the amount of light projected beyond the closely and loosely wound sections of the filament wire is caused to operate a cutting tool to sever said wire at definite intervals. In this manner the operation of the cutting tool is controlled by the spacing between the loosely coiled sections of filament wire thereby resulting in greater uniformity of the filament lengths. Further features and advantages of our invention will appear from the following detailed description of species thereof and from the drawings.

In the drawings, Fig. 1 is a perspective view of the main parts of a machine comprising our invention; Fig. 2 is a horizontal section at an enlarged scale of the portion of the machine in which the wire is severed into lengths; and Fig. 3 is a diagrammatic view showing the position of the cutting knives and light-sensitive cell with respect to the coiled filament.

Referring to the drawings, the spool 10 carries the filament wire 11 which consists of alternate closely and loosely coiled sections 12 and 13 respectively which are still in place on the mandrel 14 (Fig. 3). The said coiled sections are in this instance formed from previously coiled wire so that the structure is of the coiled-coil type. The wire 11 is withdrawn from the spool 10 by a uniformly driven sheave 15. In order to assure that the wire is uniformly withdrawn, it is pressed against the periphery of the sheave 15 by an endless belt 16 which is carried by rollers 17, 18 and 19.

Upon passing from the sheave 15, the wire 11 is pushed through a head 20 which carries inlet and outlet guide nozzles 21 and 22 respectively and an insert plug 23 having an aperture 24 therein adjacent to the path of travel of the wire 11. A light source 25, preferably an incandescent electric lamp, is located adjacent the head 20 and is adapted to cast a beam of light through a funnel 26 and through the aperture 24 in insert 23 transversely across the path of the wire 11. The light projected beyond the wire 11 passes through a tube 27 and falls on a light-sensitive cell 28, preferably a photocell, in a housing 29. Next to the head 20 is located another head 30 which carries a guide nozzle 31 and has a passage 32 therein communicating with the passage 33 for the wire 11, the passage 32 being connected with a compressed air line 34. Next to the head 30 is located a third head 35 carrying inlet and outlet nozzles 36 and 37 respectively and a container 38 for small pieces of excess wire.

The cutting arrangement comprises two knives 39 and 40 each arranged adjacent to and adapted to be moved across the faces 41 and 42 respectively of the guide nozzles 22 and 37. The knife 39 is carried by an arm 43 and the knife 40 is carried by a curved angular lever 44. The arm 43 and lever 44 are mounted on a common shaft 45 which is mounted in a bearing block 46 on the machine frame. Rollers 47 and 48 on the ends of the lever 44 engage disc cams 49 and 50 respectively which are carried by a shaft 51 which also carries a small gear 52 and is mounted in a bearing block 53. The disc cam 49 is provided with a raised edge portion 54 while the cam 50, at a diametrically opposite point, is provided with an edged depression 55.

The gear 52 meshes with a large gear 56 carried by a shaft 57 which also carries a Geneva gear wheel 58. The said Geneva gear wheel 58 is rotated by engagement with a roller 59 on an arm 60 which is mounted on a sleeve 61 and is prevented from overturning by a disc 62 also mounted on the sleeve 61. The sleeve 61 surrounds a shaft 63 which carries a gear 64 and is continuously rotated by a driven gear 65 meshing with said gear 64. The left end of the sleeve 61 is elastically held against the right face of the gear 64 by an elastic element 66. The shaft 63 also carries a ratchet wheel 67.

The sleeve 61 carries at its right end an arm 68 on the end of which are pivotally mounted two angular pawls 69 and 70. The lower legs 71 and 72 of said pawls are provided with hooks 73 and 74 respectively which are pivotally mounted on the upper legs 75 and 76 of two angular pawls 77 and 78. The upper legs 75 and 76 are pivotally mounted on the lower legs 71 and 72 respectively of the angular pawls 69 and 70.

and 74 which are displaced with respect to each other by one half tooth pitch of the ratchet wheel 67.

Above the coupling arrangement 67, 69 and 70 is arranged an electro-magnet 75 which is connected to the light-sensitive cell 28 by means of conductors 76 and 77 through an amplifying arrangement 78. The armature 79 of the electro-magnet 75 is mounted on a shaft 80 which also carries a hook-shaped finger 81 which is normally held down to engage the upper legs 82 and 83 of the pawls 69 and 70 by a spring 84.

In operation, when a closely coiled portion 12 of the filament wire 11 is in front of the aperture 24 in head 20, only a small part of the light from the source 25 falls upon the photoelectric cell 28 since the said closely coiled portion 12 almost completely obstructs the said aperture 24. However, when a loosely coiled portion 13 of the said wire 11 appears in front of the said aperture 24 a greater amount of light is projected upon the cell 28 and its conductivity is therefore increased. The said cell then energizes the electro-magnet 75 through the amplifier 78. The armature 79 is then attracted by the coil of the electro-magnet 75 and the finger 81 is swung upwardly, thereby releasing the pawls 69 and 70 and permitting one of the hooks 73 or 74 to drop down and engage one of the teeth in the ratchet 67. Since the said ratchet wheel 67 is keyed to the continuously driven shaft 63, pawls 69 and 70 and the arm 68 are rotated therewith as well as the arm 60 which, together with the arm 68, is rigidly secured to the sleeve 61. The rotation of the arm 60 through its roller 59 causes the Geneva gear wheel 58 to be rapidly rotated a quarter turn, and through the shaft 57 and gear 56 the gear 52 is caused to make one rapid rotation about its axis. The rotation of gear 52 causes the disc cam 49 to be rotated so that the projection 54 thereon engages the roller 47 on the lever 44, thereby causing said lever 44 as well as the arm 43 to be pivoted on the shaft 45 causing the knives 39 and 40 to move across the wire 11 to sever it. In order to prevent the roller 47 from leaving the disc cam 49 the second disc 50 is provided with the depression 55 therein which is engaged by the roller 48 when the roller 47 engages the projection 54, thereby imparting a positive motion to the lever 44 and knives 39 and 40. In the meantime the intermediate or loosely coiled portion 13 of the filament wire 11 which causes the excitation of the magnet 75 has been moved to a position in front of the knife 39 so that when said knife 39 is moved forward the said intermediate portion 13 is cut through at its center. After the knife 39 has swung back the disc 49 and the ratchet wheel 67 continue to rotate until the legs 82 and 83 of the pawls 69 and 70 strike the finger 81 which in the meantime has been lowered by the spring 84 due to deenergization of the magnet 75. The same cycle is then repeated when the next loosely coiled portion 13 of the filament wire 11 appears in front of the aperture 24.

When severing the filament wire 11 at the middle of the loosely coiled portion 13 it is only necessary to employ the one knife 39. However, we prefer to employ two knives 39 and 40 which, as shown in Fig. 3, are spaced apart a distance which is less than the distance from center to center of two successive intermediate portions 13 of the filament wire 11. In this case, when the starting point *a* of a loosely coiled portion 13 ap-

pears in front of the aperture 24, the cell 28 will function to cause the knives 39 and 40 to be operated. The time lag is so adjusted that the knife 39 cuts this intermediate portion 13 when its starting point *a* appears at position *c*. As shown in Fig. 3, the knife 39 is arranged so that it does not sever the loosely coiled portion 13 in the center plane *y*—*y* but rather a short distance ahead of this plane. When the knives are next actuated, the end point *b* of the same loosely coiled portion will be located at *d* so that the remainder 13' thereof will be cut to the proper length by the knife 40 arranged behind the center plane *z*—*z*. A short length of wire 13'' will drop into the container 38 as waste. Since the knives 39 and 40 function simultaneously the length of the individual filaments will be equal to the distance between the two knives. The severed filaments are blown out of the machine into a suitable container by compressed air supplied through the line 34.

In some types of coiled filaments the closely coiled portions 12 have short intermediate sections similar to the loosely coiled sections 13 which are engaged, in the finished lamp, by the support wires. In that case it is of course necessary to prevent the severing of the filament wire when one of said short supporting sections appears in front of the aperture 24. This may be done by so designing the insert 23 in the head 20 that the magnet 75 will be energized only when one of the long loosely coiled portions passes the said aperture. When a short intermediate part passes the said aperture, the cell will not obtain sufficient light to actuate the magnet 75 since only a part of the aperture is uncovered, while the other part is covered by a closely coiled section of the filament wire. It is also possible to arrange two light sources adjacent each other to the same end.

What we claim as new and desire to secure by Letters Patent of the United States is:

1. The method of severing into lengths coiled filament wire having alternately closely and loosely wound sections which comprises moving the filament wire longitudinally through a beam of light and causing the variation in the amount of light projected beyond said closely and loosely wound sections of filament wire to intermittently operate a cutting tool to sever said wire at intervals.

2. The method of severing into lengths coiled filament wire having alternately closely and loosely wound sections which comprises moving the filament wire longitudinally through a beam of light directed toward a light-sensitive cell and causing the variation in the amount of light projected beyond said closely and loosely wound sections of filament wire upon said light-sensitive cell to intermittently operate a cutting tool to sever said wire at intervals.

3. The method of severing into lengths coiled filament wire having alternately closely and loosely wound sections which comprises moving the filament wire longitudinally through a beam of light directed toward a light-sensitive cell and causing the increase in the amount of light projected beyond said loosely wound sections of filament wire upon said light-sensitive cell to intermittently operate a cutting tool to sever said wire into lengths.

4. Apparatus for severing into lengths coiled filament wire having alternately closely and loosely wound sections comprising means for continuously moving said wire longitudinally of its

axis, a light source disposed adjacent the path of said wire and adapted to project a beam of light transversely across the said path of said wire, a cutter disposed adjacent the path of said wire, and means disposed adjacent the path of said wire on the opposite side from said light source and in the path of the beam projected therefrom for causing the variation in the amount of light projected thereon past said closely and loosely wound sections of filament wire to intermittently actuate said cutter to sever said wire at intervals.

5. Apparatus for severing into lengths coiled filament wire having alternately closely and loosely wound sections comprising means for continuously moving said wire longitudinally of its axis, a light source disposed adjacent the path of said wire and adapted to project a beam of light transversely across the said path of said wire, a cutter disposed adjacent the path of said wire, and a light-sensitive cell disposed adjacent the path of said wire on the opposite side from said light source and in the path of the beam projected therefrom for causing the variation in the amount of light projected thereon past said closely and loosely wound sections of filament wire to intermittently actuate said cutter to sever said wire at intervals.

6. In a device for severing into lengths coiled filament wire having alternately closely and loosely wound sections, means for continuously moving said wire longitudinally of its axis, a pair of knives disposed adjacent to the path of travel of said wire and spaced apart a distance less than the distance between centers of successive loosely wound sections, and means for actuating said knives to cause them to sever said wire a short distance on opposite sides of the centers of said loosely wound sections to form individual lengths of wire consisting of a closely coiled section with loosely coiled sections of predetermined length at each end thereof.

7. In a device for severing into lengths coiled filament wire having alternately closely and loosely wound sections, means for continuously moving said wire longitudinally of its axis, a pair of knives disposed adjacent to the path of travel of said wire and spaced apart a distance less than the distance between centers of successive loosely wound sections, a light source disposed adjacent the path of said wire ahead of said knives and adapted to project a beam of light transversely across said path, and a light-sensitive cell disposed adjacent said path of said wire on the opposite side from said light source and in the path of the beam projected therefrom for causing the variation in the amount of light projected thereon past said closely and loosely wound sections of filament wire to actuate said knives to cause them to sever said wire a short distance on opposite sides of the centers of said loosely wound

sections to form individual lengths of wire consisting of a closely coiled section with loosely coiled sections of predetermined length at each end thereof.

8. Apparatus for severing into lengths coiled filament wire having alternately closely and loosely wound sections comprising a head having a passage therethrough for said wire, means for continuously moving said wire longitudinally through said passage, a light-sensitive cell disposed adjacent to one side of said head, a light source disposed adjacent to said head on the opposite side from said cell for directing a beam of light through a transverse aperture in said head across the path of said wire toward said cell, means for excluding substantially all light from said cell other than that projected by said light source, a cutter disposed adjacent to the path of said wire, and means controlled by said light-sensitive cell for causing the variation in the amount of light projected upon said cell past said closely and loosely wound sections of filament wire to actuate said cutter to sever said wire at intervals.

9. Apparatus for severing into lengths coiled filament wire having alternately closely and loosely wound sections comprising means for continuously moving said wire longitudinally, a light source disposed adjacent the path of said wire, a light-sensitive cell disposed adjacent the path of said wire on the opposite side from said light source and in the path of the beam projected therefrom, a cutter disposed adjacent the path of said wire, mechanism for actuating said cutter, driving mechanism comprising a constantly driven shaft having a ratchet wheel thereon, a pawl forming a coupling between said ratchet wheel and said cutter-actuating mechanism, and an electro-magnet adjacent said pawl normally holding it out of engagement with said ratchet wheel whereby the variation in the amount of light projected from said light source past said closely and loosely wound sections of filament wire upon said light-sensitive cell causes said cell to actuate said electro-magnet to release said pawl and permit it to engage said ratchet wheel to couple the said cutter-actuating mechanism thereto and cause the said cutter to sever the wire.

10. Apparatus as set forth in claim 9 in which the cutter-actuating mechanism comprises a Geneva gear wheel, a sleeve on the said constantly driven shaft having a pair of arms extending therefrom, one of said arms carrying said pawl and the other arm having a roller thereon for engaging with said Geneva gear wheel and causing it to be rotated upon engagement of said pawl with the said ratchet wheel to actuate the said cutter.

HEINRICH ASMUSSEN.

JOS. RIESS.
